CLAIM

The ornamental design for an omnidirectional HID lamp, as shown and described.

DESCRIPTION

FIG. 1 is a rear, lower perspective view of a first embodiment of an omnidirectional HID lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear, lower perspective view of a second embodiment of an omnidirectional HID lamp showing our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the drawings are for illustrative purposes and represent unclaimed portions of the portion of the omnidirectional HID lamp and therefore form no part of the claimed design.
